ETTA L. JENKINS.

UNITED STATES PATENT OFFICE.

ETTA L. JENKINS, OF NEW YORK, N. Y., ASSIGNOR TO THE BUTTERICK PUBLISHING COMPANY, (LIMITED,) OF SAME PLACE.

DESIGN FOR A MISS'S COSTUME.

SPECIFICATION forming part of Design No. 17,776, dated October 11, 1887.

Application filed August 8, 1887. Serial No. 246,401. Term of patent 3½ years.

To all whom it may concern:
Be it known that I, ETTA L. JENKINS, of the city, county, and State of New York, have invented and produced a new and original 5 Design for a Pattern of a Miss's Costume; and I do hereby declare that the engraved prints accompanying this specification convey to any one accustomed to using paper patterns a clear understanding of how a garment made up by 10 the pattern will appear.

The design shows a basque and a round walking-skirt. The basque exhibits jacket-fronts curving away from the tops of the shoulders and displaying between them a vest 15 that is seen in V shape above plaited and crossed surplice ornaments, a close-fitting back that describes at the bottom two small pointed tabs superimposed upon a plaited skirt section, a standing collar, and coat-sleeves. The skirt displays a back drapery that falls in 20 straight plaits at the left side and is lifted high at the right side, where the outline is rounding. Some of the plaits at the left side turn forward and the others backward, and two short front draperies, the right drapery 25 appearing to be much deeper than the left.

What I claim as my invention, and desire to secure by Letters Patent, is—

The design for a miss's costume, as shown in the engraved print accompanying this 30 specification.
